MOTOR-DRIVEN COMPRESSOR

Richard T. Cornelius, Minneapolis, Minn.

Application October 1, 1943, Serial No. 504,556

11 Claims. (Cl. 230—182)

1

My invention relates to motor driven compressors and has for an object to produce an extremely practical and efficient compressor for compressing air and other fluids to relatively high pressures.

Another object of the invention resides in providing a relatively light and compact construction.

An object of the invention resides in providing a multiple step compressor in which the disadvantages due to freezing of condensation are overcome.

A still further object of the invention resides in the specific arrangement of the compressor, the reservoir and connecting conduits by means of which flow of air to the reservoir is maintained at all operating temperatures.

A still further object of the invention resides in providing a multiple step compressor in which the air or other fluid compressed is successively delivered from one stage to the other and to a reservoir through conduits arranged so as to cool the fluid and to cause condensation in the fluid to drain toward the following compressor unit or reservoir.

Another object of my invention resides in providing a construction by means of which the operating parts may all be readily lubricated, whereby the compressor can be run at a high rate of speed.

A still further object of the invention resides in providing mechanism for controlling the final pressure of the compressor.

Further objects of the invention reside in the novel combination and arrangement of parts and in the details of construction hereinafter illustrated and/or described.

In the drawings:

Fig. 1 is a plan view of a motor driven compressor illustrating an embodiment of my invention.

Fig. 2 is a vertical sectional view taken on line 2—2 of Fig. 1.

Fig. 3 is a fragmentary vertical sectional view taken on line 3—3 of Fig. 1.

Fig. 4 is a fragmentary vertical sectional view taken on line 4—4 of Fig. 1.

Fig. 5 is a detailed sectional view taken on line 5—5 of Fig. 2.

Fig. 6 is an elevational view showing the compressor and reservoir in position.

My invention comprises an electric motor 10 which operates three compressor units 11, 12 and 13. The compressor unit 11 is a low pressure unit, the compressor 12 is an intermediate pressure unit, while the compressor 13 is a high pressure unit. These various parts are carried by a case which is indicated in its entirety by the reference numeral

2

14. The high pressure unit 13 discharges into a reservoir 20. These parts will now be described in detail.

The motor 10 consists of a housing 15 which supports a stator core 16. The core 16 is constructed in the usual manner and carries coils 17 which form the field of the motor. Within the core 16 is rotatably mounted an armature 18 which has the usual winding 19 thereon connected to the bars of a commutator 21. The armature 18 is mounted on an armature shaft 22 which is journaled at its upper end in a bearing 23 mounted in an end bell 24 which is secured to the upper end of the housing 15. The end bell 24 carries brush holders 25 in which brushes 26 are slidably mounted for engagement with the commutator 21. The other end of the armature shaft 22 is rotatably mounted in a bearing 27 carried by a partition 28 extending across the case 14. This partition divides the case 14 into an upper compartment 35 in which a portion of the motor 10 extends and a compartment 36 serving as the crank case for the various compressor units. A seal 29 encircling the shaft 22 and mounted in the partition 28 prevents the passage of air or lubricant from the crank case 36 to the motor compartment 35. For the purpose of cooling the motor 10, air holes 213 are formed in the motor housing 15 below the armature 18 and other air holes 214 in the end bell 24 above said armature.

The lower end of the armature shaft 22 is threaded as indicated at 31 to receive a crank 32 which is rigidly screwed thereon. This crank is provided with a crank pin 30 to which is attached a ball bearing 33 which serves to operate the various compressor units. The crank 32 is provided with a counterweight 34 which counterbalances the weight of the crank 32, the bearing 33 and the other parts connected therewith.

40 The low pressure compressor unit 11 is best shown in Fig. 2 and consists of a cylinder 37. Cylinder 37 is formed with a bore 38 which extends through the same and is closed at its outer end by means of a cylinder head 39. The inner end of the cylinder 37 which is indicated by the reference numeral 41, extends through an opening 42 in the case 14. Screws 43 pass through a clamp 44 mounted on the end of the cylinder head 39 and are threaded into the housing 14. These screws hold the parts in proper assembled relationship. Within the bore 38 of cylinder 37 is slidably mounted a piston 45 which is operated by a connecting rod 46. Connecting rod 46 is pivotally connected at one end to the piston 45 by means of a wrist pin 47 and is formed at its

other end with a boss 48 in which the bearing 33 is mounted. As the armature shaft 22 of motor 10 rotates, the connecting rod 46 and the piston 45 are reciprocated.

The cylinder head 39 is formed hollow to provide a compartment 51 within the same opening at its outer end and closed at its inner end by a wall 52 forming part of said cylinder head. The wall 52 is provided with a valve seat 53 which encircles the same near the outer periphery thereof. Extending through this valve seat are a number of openings 54 which bring the bore 38 of cylinder 37 into communication with the chamber 51. A disk valve 55 seated on the valve seat 53 serves to close the valve and obstruct passage through the openings 54. The disk valve 55 is normally held seated against the valve seat 53 by means of compression coil spring 56, which at one end engages said valve disk and at its other end engages a flange 57 formed on a tubular stop 58. The flange 57 is clamped in position in a rabbet 59 formed in the end of the cylinder head 39. Said flange is held in position by means of a cap 61 which bears against said flange and is also received within the rabbet 59. The cap 61 is urged into position by means of the clamp 44 and the screws 43 previously referred to. The stop 58 serves to hold the spring 56 in proper position and the end thereof terminates short of the valve disk 55 and limits the movement of said disk away from the valve seat 53. In this manner, the distance that the valve disk raises is limited so that a short travel for the valve disk is provided and a minimum loss of the fluid compressed is produced when the piston reaches the end of its stroke.

Air is introduced into the cylinder 37 through a crescent-shaped port 62 which is formed in the cylinder 37 at the proper locality. The air entering the bore 38 of cylinder 37 passes through an air filter 63 which is constructed with a case 64 having a chamber 65 within the same open to the exterior. A pad of filter material 66 extends across the opening in chamber 65 and is held in position by means of two reticulated plates 67 and 68. The case 63 has a pipe fitting 69 formed on it which is screwed into a threaded hole 71 formed in the cylinder 37 which communicates with the port 62.

The fluid compressed is conducted from the chamber 51 through a pipe fitting 72 which is threaded into the cylinder head 39 and communicates with said chamber. This pipe fitting has a tube 73 connected to it which, in turn, delivers the compressed fluid to the compressor unit 12 as will be presently described.

For a purpose to be presently described, the low pressure cylinder 37 is of ample proportions to furnish the fluid utilized by the other two cylinders. Under certain conditions, its capacity exceeds that required and for this purpose, a pressure relief valve indicated in its entirety by the reference numeral 74 is employed. This relief valve is shown in Fig. 2 and is constructed as follows: In the center of the cap 61 is formed a discharge opening 75 which is encircled by a valve seat 76. This opening communicates with a chamber 78 formed in the clamp 44 which, in turn, communicates with the exterior through openings 79 in said clamp. A disk valve 77 seats against this seat and is urged into engagement therewith by means of a compression coil spring 80 which at one end engages said disk valve and at its other end engages the clamp 44. When the pressure within the chamber 51 becomes too

great, the valve 74 is opened and the excess fluid escapes through the opening 75 in the cap 61 and through the openings 79 in the clamp 44 to the exterior.

The intermediate pressure compressor unit 12 is best shown in Fig. 4 and comprises a cylinder 82 having a bore 83 therein of smaller dimensions than the bore 38 of cylinder 37. The end 111 of the cylinder 82 is received in an opening 112 formed in the case 14. Said cylinder has a flange 113 extending outwardly therefrom, which is secured to the said case by means of screws 114 passing through said flange and screwed into the case. In the bore 83 is slidably mounted a piston 84, which is connected by means of a wrist pin 85 to a connecting rod 86. Connecting rod 86 is pivotally connected to the boss 48 of connecting rod 46 by means of another wrist pin 87. As the crank 32 operates, piston 84 is reciprocated within the bore 83 of the cylinder 82. At the outermost end of the cylinder 82 is formed a tubular extension 88 which has a bore therein providing a chamber 89 of dimensions somewhat greater than the diameter of the cylinder bore 83. Disposed within said chamber and encircling bore 83 is a valve seat 91. A valve disk 92 seats on said seat and controls the flow of fluid from the cylinder 83. A compression coil spring 93 acts between said valve disk and a flange 94 formed on a tubular stop 95 similar to the stop 58 of the compressor unit 11. This stop has an annular portion 96 which fits within the bore of the tubular extension 88 and which is held in place therein by means of a ring 97 seated in a groove 98 in the wall of said tubular extension. A number of openings 99 in the flange 94 bring the chamber 89 into communication with a passageway 101 formed in a tube fitting 102. The tube fitting 102 is attached to the end of the tubular extension 88 by means of a clamp nut 103 which is screwed upon threads 104 formed upon the exterior of the tubular extension 88. The fitting 102 has a tube 106 brazed or otherwise secured to it and conducts the fluid entering the passageway 101 to the high pressure compressor unit 13.

The fluid to be compressed enters the cylinder bore 83 through a crescent shaped port 107 which is formed in the wall of the cylinder 82. This port communicates with a passageway 108, which, in turn, communicates with a tube fitting 109 screwed into the cylinder 82. The tube 73 previously referred to, is connected to this fitting.

The high pressure compressor unit 13 is shown in detail in Fig. 4 and is similar to the unit 12. This unit comprises a cylinder 115 having a bore 116 therein extending completely through the same. Said cylinder is constructed with an extension 117 which is received in a hole 118 in the case 14 opposite the hole 112. The cylinder 115 has a flange 119 extending outwardly therefrom which is secured to said case by means of screws 121. In the cylinder 115 is slidably mounted a piston 122 which is formed with an enlarged end 123. A connecting rod 124 is connected to the end 123 of piston 122 by means of a wrist pin 125. The said connecting rod is further connected by means of another wrist pin 126 with the boss 48 of connecting rod 46. It will thus be seen that as the crank 32 rotates, the connecting rod 124 and the piston 122 are reciprocated.

The cylinder 115 is constructed with a tubular extension 127 similar to the tubular extension 88 which is formed with a bore providing a chamber 128 within the same and having a diameter somewhat larger than the bore 116. Encircling the

bore 116 is a valve seat 129 similar to the valve seat 91 which is closed by means of a disk valve 131. Valve 131 is normally held seated by means of a compression coil spring 132 which at one end bears against said valve disk and at its other end against a stop 133. The stop 133 is similar to the stop 95 and is attached to the tubular extension 127 in the same manner. Secured to the outer end of said tubular extension is a tube fitting 134 which has a tube connector 135 formed thereon. This fitting is held in place by means of a clamp nut 136 similar to the clamp nut 103. The fluid to be compressed is delivered into the cylinder 115 through a port 137 formed in the cylinder 115. A tube fitting 138 is screwed into the cylinder 115 and communicates with this port. This tube fitting has connected to it the tube 106 leading from the intermediate pressure compressor unit 12.

The various compressor units are lubricated by means of a lubricating oil pump 141 illustrated in detail in Fig. 2. Beneath the case 15 is mounted an oil sump 142. This oil sump is in the form of a tubular receptacle with a bottom 143 and a cylindrical wall 144. The wall 144 is constructed at its upper end with an offset 145 which extends about a lip 146 formed on the lower end of the case 15. A gasket 147 carried by this lip engages the inner surface of the offset 145 and forms a fluid-tight connection therebetween. The sump 142 is detachably held secured to the case 14 by spring clips 148 best shown in Fig. 3, which snap under the offset 145. These clips have finger pieces 149 by means of which the same can be disengaged from the offset. Screws 151 hold said clips attached to the case 14.

Within the sump 142 is mounted a cylindrical housing 152. This housing has three ears 153 formed thereon, which are secured by means of screws 155 to bosses 154 extending inwardly from the lip 146 of case 14. The housing 152 has an upper end wall 156 and a partition 157 spaced from the extreme lower end thereof. In the end wall 156 and in the partition 157 are provided bearings 158 and 159 which rotatably support a vertical extending shaft 161. The shaft 161 extends upwardly into the crank case compartment 36 and has attached to its protruding end a driving member 162. The driving member 162 has a flange 163 through which an extension 164 of the crank pin 30 of the crank 32 extends. The shaft 161 is coaxial with the armature shaft 22 so that as the armature 18 rotates, shaft 161 is driven in unison with it. Within the cylindrical housing 152 and by means of the partition 157 is formed at the lower end of said housing a downwardly opening compartment 165. Shaft 151 extends into this compartment. Attached to the lowermost end of the shaft 161 and disposed within the compartment 165 is the rotor 166 of a centrifugal pump, indicated in its entirety by the reference numeral 167. A discharge passageway 168 is formed in the housing 152 and communicates with the compartment 165. This passageway extends into the crank case compartment 36 and is adapted to discharge the oil from the sump 144 into the crank case, where the same lubricates the various pistons, connecting rods, crank and wrist pin bearings. The surplus oil drains back into the sump 142 between the ears 153. In this manner, all of the operating parts of the device except the motor bearings, are lubricated.

The entire compressor is cooled in the following manner: All of the cylinders of the compressor units 11, 12 and 13 have radiating fins 171 ex-

tending outwardly therefrom. In addition, the clamp nuts 103 and 136 of the compressor units 12 and 13, respectively, are also formed with radiating fins 172. At the top of the device and attached to the protruding end 173 of the armature shaft 22 is a fan 174. This fan is of a greater diameter than the diameter of the crank case 14 and the motor housing 15 and serves to force air downwardly along the same. Part of the air so conducted passes through the fins of the various compressor units 11, 12 and 13, and cools the same. Another portion of the air is forced by said fan through the holes 214 in end bell 24 and is directed into the motor compartment 35. The air leaves this compartment through the holes 213 formed in the case 14. A guard 175, secured to the end bell 24, protects the fan 174.

In order to control the operation of the device, an automatic switch mechanism is employed which is mounted in a switch box 177 which is attached to the motor housing 15. This switch box has side walls 178 and 179, upper and lower walls 180 and 182 and a rear wall 183. The wall 183 has ears 184 projecting outwardly therefrom through which cap screws 185 extend. These cap screws are threaded into the housing 15 and serve to attach the switch box to the device. Mounted within the box 177 is an electric switch 181, which is connected in the circuit operating the motor 10. A plug 190, carried by the wall 179 or box 177 permits it connecting the motor to a source of electric energy. Inasmuch as the switch 181 forms no particular feature of the instant invention, the construction thereon has not been shown in detail. This switch, however, has a button 186 projecting outwardly therefrom, which is normally urged outwardly through suitable spring means and which, upon depression, is adapted to open the switch. When pressure is relieved on this button, the switch automatically closes.

The switch 181 is operated by means of the following construction: Formed on the wall 178 of box 177 is a boss 187, which is threaded to receive a bushing 188. A tube connector 189 is screwed into this bushing and has connected to it a tube 191. Tube 191 is connected to the fitting 134 of the compressor unit 13 and brings the chamber 192 within the bushing 188 into communication with the high pressure side of the compressor unit 13. Extending across the end of the bushing is a diaphragm 193 which is clamped by means of said bushing against a seat 194. A follower 195 bears against the under side of the diaphragm 193. Mounted for swinging movement within the box 177 is a lever 196, which is pivoted on a fulcrum 197 which is attached to a boss 200 on the rear wall 183 of box 177. A link 198 extends between the lever 196 and the follower 195 and transmits motion of the diaphragm 193 to said lever 196. The extreme end of lever 196 is engaged by a spindle 199 which has a conical head 201 at the extreme end thereof which is seated in a suitable socket 202 in said lever. Spindle 199 is slidably mounted in a guide 202 screwed into a boss 204 issuing inwardly into the box 177 from the wall 179 thereof. A compression coil spring 205 encircles the spindle 199 and urges the same into engagement with the lever 196. Movement of the lever 196 in a counter-clockwise direction is terminated by means of an adjustable stop 206 which is carried by the wall 178 of box 177. The lever 196 carries 75 an adjustable stud 207 which engages the button

186. As the diaphragm 193 moves, lever 196 is oscillated and operation of the switch 181 occurs. When the pressure produced by the high pressure unit 13 reaches the desired amount which can be adjusted by means of the stud 207, switch 181 is opened and compressor stops.

For the purpose of supporting the compressor, the box 177 is constructed with ears 211 which project outwardly therefrom. These ears have holes 212 therein through which suitable fasteners may extend to attach the compressor to a vertical support. The compressor is preferably mounted above floor level, so that the oil sump 142 may be easily removed therefrom for the purpose of filling and inspection.

In conjunction with my motor-driven compressor, I employ a reservoir such as designated at 215 in Fig. 6 and into which the compressed air or gas is directed. This reservoir is tubular in form, having a cylindrical wall 231, a lower end 232 and an upper end 233. This reservoir is constructed in two halves, 216 and 217 welded or soldered together at the center, as indicated at 218. The reservoir 215 is arranged in vertical position and is mounted on the support to which the compressor is attached. For the purpose of illustration, a channel frame member 219 has been shown for this purpose. This frame member may be a portion of the aeroplane or other structure in which the compressor is to be used. Bolts 221 extend through the ears 211 of the compressor switch box 177 and through the web 222 of the channel 219. Spacers 223 between said ears and web hold the compressor in proper position.

The reservoir 215 has attached to it a mounting plate 223. This mounting plate has secured to it bands 225 which encircle the reservoir proper and clamp the mounting plate in position. The plate 224 overlies the web 222 of channel 219 and the bolts 221 pass through the same. In this manner, the reservoir 215 is mounted in proximity to the compressor and is supported by the same support.

The tube connector 135 which is formed on the tube fitting 134 associated with the compressor unit 13 has connected to it a tube 226. This tube is connected to a tube fitting 227 which is screwed into a boss 228 secured to the reservoir 215. The inlet through the fitting tube 221 is disposed above the lower end 232 of the reservoir 215 and below the outlet in the tube fitting 234. It will thus be seen that the tube 226 inclines throughout its extent from the cylinder 115 to the reservoir 215 and that the discharge is located above the lower end of the reservoir to form the space 229 above said inlet in which water may collect. The tube 226 is covered with an insulating jacket 230.

Opposite the tube fitting 227 is a relief valve 234 which is threaded into a bushing 235 secured to the wall 231 of said reservoir. At the bottom of the reservoir is a drain 241 which is secured to the wall 232.

Air is led from the reservoir to a tube fitting 236 which is screwed into a bushing 237 secured to the upper end 233 of said reservoir. For the purpose of preventing water and foreign material from entering the fitting 236, a filter 238 is employed which is supported by a previous plate 239 secured to the wall 231 of the reservoir 215 below the upper end 233 thereof.

The operation of my invention is as follows: When the pressure produced by the high pressure unit 13 drops below a certain value, or when

the device is being first started, pressure on the diaphragm 193 is released and the lever 196 urged against the stop 206 by means of the spring 205. This causes the switch 181 to close and energize the motor 10. The operation of motor 10 causes simultaneous operation of the pistons within the various compressor units 11, 12 and 13, and the compression of the fluids within the cylinder thereof. When the motor-driven compressor comprising the instant invention is used at high altitudes, all of the air compressed in cylinder 37 is required to furnish the necessary amount of air at the desired pressure to be successively compressed in the cylinders 32 and 115. When, however, the compressor is used at low altitudes, an excess of air would be drawn into the cylinder 37. For the purpose of disposing of the excess air, the relief valve 74 is employed. Spring 80 operating this valve is so designed as to relieve the pressure in cylinder 37 when the amount of air pumped by the compressor unit 11 reaches the desired volume. It will be noted that the tube fitting 72 connected to the discharge end of the compressor unit 11 extends upwardly and that the tube 73 which is connected to it slopes downwardly from this fitting to the inlet fitting 109 of cylinder 82, which inlet fitting is disposed at the lowermost portion of the cylinder 82. By means of this construction, the condensation occurring in tube 73 flows downwardly from the unit 11 to the unit 12. To produce the same condition in the tube 106 which is connected to the high pressure side of the compressor unit 12, said tube extends upwardly from the fitting 102 and is then caused to travel downwardly toward its point of connection with the high pressure cylinder 115. Since the upstanding portion of tube 106 is short, condensation does not occur until the air reaches the inclined portion of the tube from which it drains into the cylinder 115 of unit 13. In this manner, condensation is caused to travel through the compressor from one cylinder to the other. When the air leaves the compressor 13, the same flows through the tube 226 and into the lower end of the reservoir 215. Due to the insulating jacket 230, freezing of the water is prevented during its passage through tube 226. Any water which may have been condensed from the liquid, flows into the bottom of said reservoir and is confined within the space 229. The air travels upwardly and passes through filter 238 prior to its discharge from the reservoir, through the tube fitting 233. By arranging the conduits between the compressor units and the reservoir as disclosed, pocketing of the condensation is eliminated and the condensation discharged through the compressor with the compressed air and into the reservoir, where separation occurs. When the pressure in the high pressure compressor unit 13 reaches the desired amount, switch 181 is automatically closed as previously described. Whereupon the compressor ceases to function.

My invention is highly advantageous in that an extremely simple and practical device is produced which will positively and effectively function to produce the desired results. With my invention, air can be compressed at different altitudes without adjustment of the apparatus. My improved motor-driven compressor can be constructed relatively light in weight, so that the same may be installed on the aeroplanes or wherever a light weight construction is desired. By means of the lubricating system employed with my invention, all of the parts are thoroughly lubricated, so that the compressor can be driven

at a higher rate of speed. With the automatic switch mechanism, the pressure is maintained any desirable value. Adjustment of the pressure can be readily made by adjusting the guide forming the spring seat for the pressure regulating device. Cooling of the compressor is procured by the motor operating the compressor units. The sump for lubricating oil is readily removed and inspection of the interior of the compressor is readily had upon removal of the same.

Changes in the specific form of my invention as herein disclosed may be made within the scope of what is claimed without departing from the spirit of my invention.

Having described my invention, what I claim as new and desire to protect by Letters Patent is:

1. A compressor comprising a case, a motor mounted on the upper portion of said case and of diametral dimensions substantially the same as those of the case said motor including an armature shaft, a plurality of compressor units projecting outwardly from said case and extending beyond the confines of said motor and case, means for operating said compressor units from the armature shaft of said motor, said case and motor having ventilating openings for conducting air through the motor, the armature shaft of said motor extending upwardly beyond the same, and a fan mounted on said armature shaft and projecting radially outwardly beyond said motor and case, said fan serving to force air past said compressor units and through said motor.

2. A multiple stage compressor comprising a case, a motor mounted on the upper end of the case and having an armature shaft extending into said case, a crank attached to said armature shaft and disposed within said case, a plurality of compressor units carried by said case and disposed radially with reference thereto and operating at different pressures, means for operating all of said compressor units from said crank, a conduit having a reach extending upwardly from the discharge of a lower pressure compressor unit and another reach inclining downwardly toward the intake of a higher pressure compressor unit, the intake of said higher pressure compressor unit being disposed at the uppermost portion thereof to cause condensation collected in said last-named reach to flow by gravity into the higher pressure compressor unit.

3. In combination, a compressor having a high pressure cylinder, a piston in said cylinder, means for operating said piston, an inlet and an outlet for said cylinder, a reservoir, a conduit extending between the outlet of said cylinder and reservoir and serving to discharge into the reservoir, said conduit inclining downwardly throughout its extent, the inlet from said conduit being above the bottom of said reservoir, an outlet at the uppermost portion of the reservoir, and a drain at the lowermost portion of said reservoir.

4. In combination, a compressor having a high pressure cylinder, a piston in said cylinder, means for operating said piston, an inlet and an outlet for said cylinder, a reservoir, a conduit extending between the outlet of said cylinder and reservoir and serving to discharge into the reservoir, said conduit inclining downwardly throughout its extent, an insulating jacket surrounding said conduit, the inlet from said conduit being disposed intermediate the upper and lower ends of the reservoir, an outlet at the uppermost portion of the reservoir and a drain in the reservoir at a locality below said inlet.

5. A compressor comprising a case, a motor

mounted on the upper end of the case and having an armature shaft extending into said case, a crank attached to said armature shaft and disposed within said case, said crank including a crank pin, a plurality of compressor units carried by said case and disposed radially with reference thereto, means for operating all of said compressor units from said crank pin, an oil pump situated within said case and having a shaft extending substantially in alignment with the armature shaft, a projection on said pump shaft adapted to be engaged by the crank pin and discharge means for directing the oil pumped to the moving parts within said case.

15 6. In combination, a multiple stage compressor comprising a plurality of cylinders arranged horizontally and at substantially the same plane, pistons in said cylinders, means for operating said pistons, inlets and outlets for said cylinders, a 20 conduit extending between the outlet of a cylinder of lower pressure to the inlet of a cylinder of higher pressure, said conduit at the locality of the first named cylinder having a substantially upwardly extending vertical reach, and a reach running between said vertical reach and the other cylinder and inclined substantially throughout its extent toward the second named cylinder.

7. In combination, a compressor having a high pressure cylinder arranged in a horizontal position, a piston in said cylinder, means for operating said piston, an inlet for said cylinder, an outlet for said cylinder comprising a discharge chamber at the end of the cylinder, a vertically extending reservoir disposed adjacent said cylinder, a conduit connected to the under side of said discharge chamber and to said reservoir and serving to discharge into the reservoir, said conduit inclining downwardly throughout its extent, the inlet from said conduit to said reservoir being disposed intermediate the upper and lower ends of the reservoir, an outlet at the uppermost portion of the reservoir and a drain in the reservoir at a locality below said inlet.

8. A compressor comprising a case, a motor 45 mounted on the upper end of the case and having a vertically extending armature shaft disposed within the case, a crank attached to said armature shaft and disposed within said case, a plurality of compressor units carried by the case 50 and extending radially with reference thereto, means for operating all of said compressor units from said crank, an oil sump disposed below said case, means for detachably securing said sump to the lower end of the case, a pump housing disposed within said sump, means for detachably securing said pump to the lower end of the case, said pump having a rotor at the lowermost portion thereof, a shaft for driving said rotor, said shaft being substantially coaxial with said armature shaft, said pump shaft having an eccentric 60 part disposed adjacent a corresponding part on the crank, a pin on one of said parts and a hole in the other of said parts for the reception of said pin for restraining relative movement between

65 said shafts and forming a driving connection between said armature shaft and pump shaft and a conduit connected to the discharge of the pump and leading upwardly and discharging in proximity to the moving parts associated with said crank.

9. A compressor comprising a case, a motor mounted on the upper portion of said case and of diametral dimensions substantially the same as those of the case, a plurality of compressor units projecting outwardly from said case and extend-

ing beyond the confines of said motor and case, an oil sump disposed below said case and being of substantially the same diametral dimensions as said case, means for operating said compressor units from the armature shaft of said motor, said case and motor having ventilating openings for conducting air through the motor, the armature shaft of said motor extending upwardly beyond the same, and a fan mounted on said armature shaft and projecting radially outwardly beyond said motor and case, said fan serving to force air past said compressor unit and sump and through said motor.

10. A multiple stage compressor comprising a plurality of cylinders arranged in coplanar horizontal relation, pistons therein, means for simultaneously operating said pistons at predetermined relative speeds, said cylinders being proportioned to procure different pressures therein, a lower pressure cylinder having an inlet and a discharge outlet and the cylinder of the next higher pressure having an inlet and a discharge outlet, a conduit extending between said cylinders and having a vertical reach extending upwardly from the outlet of said lower pressure cylinder and a downwardly inclining reach extending from the uppermost portion of the vertical reach to the inlet of said higher pressure cylinder to cause most of the condensation collected in said conduit to flow by gravity into said higher pressure cylinder.

11. A multiple stage compressor comprising a plurality of cylinders arranged in coplanar horizontal relation, pistons therein, means for simultaneously operating said pistons at pre-determined relative speeds, said cylinders being proportioned to procure different pressures therein, a lower pressure cylinder having an inlet and having a

discharge outlet at the uppermost portion of the same and the cylinder of the next higher pressure having an outlet and having an inlet at the uppermost portion of the same, a conduit between said cylinders having a vertical reach extending upwardly from the outlet of said lower pressure cylinder and a downwardly inclining reach extending from the uppermost portion of the vertical reach to the inlet of said higher pressure cylinder to cause most of the condensation collected in said conduit to flow by gravity into said higher pressure cylinder.

RICHARD T. CORNELIUS.
